ORE SEPARATOR

Paul Hinkley, Los Angeles, Calif.

Application July 31, 1933, Serial No. 682,966

10 Claims. (Cl. 209—452)

This invention relates to a machine for separating ore from gangue and pertains particularly to a wet concentrating or separating device. It contemplates a rotary table having spiral riffles leading from the peripheral portion of the table to a central concentrate delivery opening.

The broad objects of this invention are to provide a wet concentrator, efficient in the percentage of recovery; requiring little power for its operation; compact in structure; having a small water consumption; durable; and economical in first cost and upkeep. To this end the invention comprises a structure as above described wherein the materials operated upon are all handled under water, and concentration occurs progressively from the periphery to the concentrate discharge opening at the center. The materials are stratified at the periphery, gangue discharged over the rim and the values carried upward to the center with added concentration during travel. In addition to the broader objects of this invention, there are details of structure whereby a practical concentrator is obtained.

These objects are accomplished by means of the embodiments of my invention illustrated in the accompanying drawings, in which:

Fig. 1 is a longitudinal sectional view partly in elevation of one embodiment of my invention; Fig. 2 is a front plan view of the structure shown in Fig. 1; Fig. 3 is a face view of a modified form of table; and Fig. 4 is a section as seen on the line 4—4 of Fig. 3.

Referring more particularly to Figs. 1 and 2, a frame which may be of any suitable design is indicated by 5. Extending across the frame is an adjustment bar 6 journaled in bearings 7 at the sides of the frame. A table bearing 8 is mounted at the center of bar 6 and journaled therein is the hollow shaft 9 of a rotary table or pan.

The table has a flat base 10 with a concentrate discharge opening 11 communicating with the bore of shaft 9, the opening serving as a concentrate discharge opening. A rim 12 has a return flange portion 13 and an inturned lip 14. The table is shown provided with a rubber or vulcanite liner 15 having spiral riffles 16 which communicate with the discharge opening 11 at the center. On the base of the table at shaft 9 is a bevel gear 17 for rotating the table through any suitable drive means.

In the frame 5 at the lower end of the table is a tank 18 for water and tailings. The table dips into the tank. Tailings will settle in tank 18 and may be removed by any suitable means.

An overflow pipe 19 serves to maintain a selected water level in the tank, there being an adjustment for the rise of the water pipe as shown by the coupling 20. Any other suitable adjustment means may be provided. Arms 21 extend from bar 6 and secured to one arm by a swivel connection is nut 22. A thrust bearing 23 is mounted on the frame. Journaled in bearing 23 and threaded into nut 22 is an adjustment rod 24 having a hand wheel 25 secured thereto for convenient manipulation. By turning the hand wheel, the bar 6 may be rocked and the inclination of the table adjusted.

Secured between arms 21 is a cross member 26. Arms 27 are provided having clamps 28 embracing rod 26 so that the arms may be adjusted angularly on cross member 26. Mounted on and extending between arms 27 is a tubular member 28 having a T fitting 29 connected to one end, the other end being closed. A leg of fitting 29 has a tubular section connecting it to one leg of a T fitting 30 forming a part of member 26. The opposite leg of fitting 29 is connected to a solid section completing member 26. Jet nozzles 31 are disposed in the tubular member 28. A flexible hose 32 is connected to a source of supply for dressing water. The jet nozzles 31 are for the purpose of delivering dressing water onto the table and are located so that they are on the side of the table in advance of a vertical plane passing through the axis of rotation of the table. The direction of rotation is such that material in the riffles 16 will travel therealong toward the concentrate discharge opening, that is, there is an involution of the material.

By turning the tubular member 28, the angle of the direction of the jets 31 may be adjusted. By adjusting arms 27 on cross member 26, the distance and position of the jets with respect to the table may be changed. After adjustment of the spray means, the latter will be maintained in the same position relative to the table regardless of the adjustment of the inclination of the latter. A wash pipe 33 has a nozzle directed into the peripheral trough of the table, washes the material therein and prevents it from climbing up the trough.

A baffle plate 34 is secured by arms 35 to bar 26 and extends over the lower left hand corner of the table with its outer advanced edge lying close to lip 13 and the edge at the lower following portion receding from the trough.

Any suitable ore feeding means as 36 may be employed depending on the character of the ore. The feeding means is disposed to deliver ore to

the table on side of the table opposite to the spray means or the following side.

The table is rotated and material to be concentrated fed, from feeding means 36 onto the table. 5 The trough prevents the material from falling off the table. The material settling in the trough at the lower part of the table where it is tumbled under water between baffle plate 34 and the table and stratified, the values settling and the 10 gangue rising. The riffles 16 pick up the values, elevating them and carrying them to the left on the lower advancing side of the table where they are further washed and concentrated by the action of the spray means and the rotating table. 15 Eventually the concentrates are carried to the discharge opening 11 and delivered to any suitable receptacle. The material in the riffles is tumbled and the gangue on the top washed downwardly as the material is advanced to the left 20 with an upward urge. The material captured between the table and baffle plate is thoroughly tumbled so as to precipitate the values. The baffle plate prevents the material from being washed over the edge of the trough before sufficient stratification takes place for efficient action by the riffles. The gangue is washed over the trough through the clearance between the following edge of the baffle plate 34 and the trough. 25

Adjustment of the inclination of the table, the 30 position and direction of the dressing water spray and the relation of the baffle plate may be made to accommodate the concentrator to material of various characters. The tailings settle in tank 18, the water passing through overflow pipe 19 and made available for further use, resulting in economy of water consumption. The trough is an 35 important feature of the invention as it retains the material long enough to insure efficient precipitation. Without means resisting travel over the edge of the trough, the material is washed from the top before sufficient tumbling has taken place and a high percentage of values is washed with the gangue into the tailings tank.

Figs. 3 and 4 show a modified form of table 40 wherein there is a central bed 37 having spiral riffles 38 and a sloping rim 39 forming a trough. The rim 39 is provided with riffles 40 which carry the material inwardly thereby restraining it from quick passage over the edge of the trough 45 and insuring retention for tumbling and stratification.

By proper design of the trough as to its extent and slope in the case of the modification shown in Figs. 3 and 4, the baffle plate may be omitted 50 from the concentrator and efficient recovery obtained in certain cases particularly placer ground. The rim 39 spreads the material aiding in the precipitation of values. By proper design of the trough shown in Figs. 1 and 2 especially as 55 to the return flange 13 and lip 14, the baffle plate may also be omitted in treating certain material, the flange and lip resisting travel of the material over the edge of the trough.

What I claim is:—

60 1. A concentrator comprising a rotatable inclined table having a rim laterally directed with relation to the table, there being a concentrate discharge opening at the center of said table, said table having spiral riffles communicating with said opening and extending to said rim for involution of material by rotation of said table; a water tank at the bottom of said table disposed with said rim to dip into the water contained therein; a stationary baffle plate overlying said table and extending within said tank; spray 65

means for dressing water ranging radially of said table above said tank and over said table on the advancing side with respect to said tank; and material feed means on the following side of said table. 5

2. A concentrator comprising a rotatable inclined table having a rim laterally directed with relation to the table, there being a concentrate discharge opening at the center of said table, said table having spiral riffles communicating with said opening and extending to said rim for involution of material by rotation of said table; a water tank at the bottom of said table disposed with said rim to dip into the water contained therein; a stationary baffle plate overlying said table and extending within said tank; spray means for dressing water ranging radially of said table above said tank and over said table on the advancing side with respect to said tank, means to adjust said spray means to change the 10 inclination and direction of the spray issuing therefrom; and material feed means on the following side of said table. 15

3. A concentrator comprising a rotatable inclined table having a rim trough laterally directed with relation to the table, said trough having means overlying the face of said table resisting travel of material radially thereover, there being a concentrate discharge opening at the center of said table, said table having spiral riffles communicating with said opening and extending to said trough for involution of material by rotation of said table; a water tank at the bottom of said table disposed with said trough to dip into the water contained therein; spray means for dressing water ranging radially of said table above said tank and over said table on the advancing side with respect to said tank, and material feed means on the following side of said table. 25 30

4. A concentrator comprising a rotatable inclined table having a rim trough laterally directed with relation to the table, said trough having means overlying the face of said table resisting travel of material radially thereover, there being a concentrate discharge opening at the center of said table, said table having spiral riffles communicating with said opening and extending to said trough for involution of material by rotation of said table; a water tank at the bottom of said table disposed with said trough to dip into the water contained therein; spray means for dressing water ranging radially of said table above said tank and over said table on the advancing side with respect to said tank; and material feed means on the following side of said table. 40 45 50

5. A concentrator comprising a rotatable inclined table having a rim trough laterally directed with relation to the table, said trough having means resisting travel of material radially thereover, there being a concentrate discharge opening at the center of said table, said table having spiral riffles communicating with said opening and extending to said trough for involution of material by rotation of said table; a water tank at the bottom of said table disposed with said trough to dip into the water contained therein; a stationary baffle plate overlying said table and extending within said tank; spray means for dressing water ranging radially of said table above said tank and over said table on the advancing side with respect to said tank; and ma- 60 65 70 75

material feed means on the following side of said table.

6. A concentrator comprising a rotatable inclined table having a rim trough laterally directed with relation to the table, said trough having means resisting travel of material radially thereover, there being a concentrate discharge opening at the center of said table, said table having spiral riffles communicating with said opening and extending to said trough for involution of material by rotation of said table; a water tank at the bottom of said table disposed with said trough to dip into the water contained therein; a stationary baffle plate overlying said table and extending within said tank; spray means for dressing water ranging radially of said table above said tank and over said table on the advancing side with respect to said tank, means to adjust said spray means to change the position and direction of the spray issuing therefrom; and material feed means on the following side of said table.

7. A concentrator comprising a rotatable inclined table having a rim laterally directed with relation to the table, said rim having an in-turned lip overlying the face of said table, there being a concentrate discharge opening at the center of said table, said table having spiral riffles communicating with said opening and extending to said rim for involution of material by rotation of said table; a water tank at the bottom of said table disposed with said rim and lip to dip into the water contained therein; spray means for dressing water ranging radially of said table above said tank and over said table on the advancing side with respect to said tank; and material feed means on the following side of said table.

8. A concentrator comprising a rotatable inclined table having a rim laterally directed with relation to the table, said rim having an in-turned lip overlying the face of said table, there being a concentrate discharge opening at the center of said table, said table having spiral riffles communicating with said opening and extending to said rim for involution of material by rotation of

said table; a water tank at the bottom of said table disposed with said rim and lip to dip into the water contained therein; spray means for dressing water ranging radially of said table above said tank and over said table on the advancing side with respect to said tank, means to adjust said spray means to change the position and direction of the spray issuing therefrom; and material feed means on the following side of said table.

5

9. A concentrator comprising a rotatable inclined table having a rim laterally directed with relation to the table, said rim having an in-turned lip, there being a concentrate discharge opening at the center of said table, said table having spiral riffles communicating with said opening and extending to said rim for involution of material by rotation of said table; a water tank at the bottom of said table disposed with said rim to dip into the water contained therein; a stationary baffle plate overlying said table and extending to said lip within said tank; spray means for dressing water ranging radially of said table above said tank and over said table on the advancing side with respect to said tank; and material feed means on the following side of said table.

10

10. A concentrator comprising a rotatable inclined table having a rim laterally directed with relation to the table, said rim having an in-turned lip, there being a concentrate discharge opening at the center of said table, said table having spiral riffles communicating with said opening and extending to said rim for involution of material by rotation of said table; a water tank at the bottom of said table disposed with said rim to dip into the water contained therein; a stationary baffle plate overlying said table and extending to said lip within said tank; spray means for dressing water ranging radially of said table above said tank and over said table on the advancing side with respect to said tank, means to adjust said spray means to change the position and direction of the spray issuing therefrom; and material feed means on the following side of said table.
